by Clarence E. Melville Atty.

UNITED STATES PATENT OFFICE.

ELMER L. OGLE, OF CHICAGO, ILLINOIS, ASSIGNOR TO FEDERAL ELECTRIC COMPANY, OF CHICAGO, ILLINOIS, A CORPORATION OF ILLINOIS.

FUSE PLUG.

Application filed October 12, 1921. Serial No. 507,218.

To all whom it may concern:

Be it known that I, ELMER L. OGLE, a citizen of the United States, and a resident of Chicago, county of Cook, and State of Illinois, have invented certain new and useful Improvements in Fuse Plugs; and I do hereby declare that the following is a full, clear, and exact description thereof, reference being had to the accompanying drawings, and 10 to letters of reference marked thereon, which form a part of this specification.

This invention relates to improvements in electric fuse plugs and consists of the matters hereinafter described and more particularly pointed out in the appended claims.

One of the objects of the invention is to provide a fuse wherein the fusible element is in the form of a refill cartridge which may be quickly removed when "blown" and readily replaced by a new one.

A further object of the invention is to so construct the plug that it will be inoperative if a current conductor other than the particular associated cartridge is inserted into 25 the plug in lieu of said cartridge.

Still a further object of the invention is to provide a cartridge holder which can only be inserted into the casing in a certain predetermined manner so that it is impossible 30 to reassemble the plug after a refill and have an inoperative plug.

These objects of the invention together with the many advantages thereof will more fully appear as I proceed with my specification.

In the drawings:

Fig. 1 is a perspective view of a fuse plug embodying my invention.

Fig. 2 is a vertical central section through 40 the fuse plug on an enlarged scale, the refill cartridge being shown partly in elevation and partly in section.

Fig. 3 is a horizontal section through the fuse plug on the line 3—3 of Fig. 2.

Fig. 4 is a perspective view of a refill cartridge holder embodied in my improved fuse plug.

Fig. 5 is a fragmentary detail sectional view showing a modified form of my invention.

Fig. 6 is a perspective view of a modified form of refill cartridge holder.

Referring now in detail to that embodiment of the invention illustrated in the ac-

companying drawings, 5 indicates the body 55 of the fuse plug which is made of a suitable insulation material. Said body is made cylindrical in cross section and the end 6 thereof is enlarged in diameter and is corrugated longitudinally to provide a gripping head. 60 Surrounding the body is a threaded contact shell 7 which includes an inturned radial end flange 8 that engages the end of the body. To secure the shell in place upon the body I provide a recess 9 in said body near the head, 65 into which a part 10 of the shell is forced, as shown in Fig. 2.

In the plug body and opening through one end thereof is provided a longitudinally extending cylindrical recess 11 in which a 70 cartridge holder 12 snugly fits. Communicating with and opening into one side of the recess 11 is a second longitudinally extending rectangular recess 13 which opens at one end, laterally through the body, just beyond the 75 gripping head. Located in the recess 13 is a spring contact member or brush 7^a which is riveted or otherwise secured to the contact shell 7. A part 14 of the recess 11 is restricted in diameter to provide longitudinal 80 extending shoulders 15 and a radial shoulder 16 near the end of the plug body.

The cartridge holder 12 has a tubular body 17 which fits within the recess 14 and a radially flanged head 18 at the outer end which 85 engages the end of the plug body and overlaps the flange 8 of the contact shell 7. A part of the body of the cartridge holder is cut away to provide shoulders 19 and 20 which are complementary to and engage the 90 shoulders 15 and 16 of the plug body so as to prevent a relative rotation between the plug body and cartridge holder. Thus, as is apparent, the cartridge holder can be inserted into the plug body in one manner only and 95 when thus inserted, will turn with said plug body when the same is threaded into a socket. The inner end of the holder 12 is reduced in outside diameter and is cut away or flattened on one side as at 21, for a purpose to appear 100 later.

The cartridge holder has a central bore 22 of a diameter equal to that of the smaller part 14 of the recess 11 of the plug body, to receive a fuse cartridge 23. This cartridge includes a fusible element 24 having an end 25 which extends to the outside of the cartridge, to provide the usual "tell tale

tag." This "tag" has impressed upon it the number for indicating the voltage at which that particular cartridge may be safely used.

As the cartridge shown herein is fully illustrated and described in my copending application, S. N. 497,888 filed September 2, 1921, the same will only be set forth in general in this instance. In the outer end of the cartridge is a metallic plug 26 to which the fusible element 24 is connected. This plug has a threaded central bore 27 and the tubular body 28 of the cartridge is secured to the plug 26 by a cap 29, there being a longitudinal slot 30 in one side of the outer end of the cartridge to receive a pin 31 carried by the holder. In the end of the bore 22 is provided a thin sheet metal apertured disc 32 of a thickness equal to the pitch of the threads on the end 33 of a screw 34 carried by the holder. This screw has a head 35 beyond the end of the body which constitutes the central contact member of the fuse plug and by means of which the end 33 of the screw may be threaded through the disc 32 and into the bore 27 of the plug 26. The disc thus acts to hold the screw against falling out of the holder but in no way interferes with the rotation of the screw. In the inner extreme end of the holder in line with the flattened side 21 thereof, is provided a notch 36 defining spaced shoulders which form a guide for the exposed end 25 of the fusible element.

Assume that the holder is removed from the plug body and it is desired to "load" the same with a cartridge. The outer end of the cartridge is inserted into the bore 22 of the holder, with the pin 31 extending into the groove 30 of the cartridge. This correctly positions the cartridge in the holder. The screw 34 being swiveled in the holder and being in line with bore 27 in the cartridge, may now be threaded into said bore. This secures the outer end of the cartridge to the holder, the pin and groove construction before mentioned preventing rotation of the cartridge when screwing in the screw 34. After this has been done, the exposed end 25 of the fusible element 24 is bent over and through the notch 36 and then into engagement with the flattened part or face 21 on the inner end of the holder.

The holder is next inserted into the recess in the plug body, the engaging shoulders 15 and 19 before described always insuring the correct registration of the parts and the shoulders 16 and 20 determining the limit of the insertion. When inserted, the "tell tale tag" or exposed bent over end 25 of the fusible element will automatically engage and be brought into electrical contact with the brush member 7^a on the plug body. The plug is now assembled.

My improved fuse plug has many advantages. A "blown" cartridge may be

easily removed and replaced by a new one and the parts are so arranged that there can be no error in the replacement.

No foreign conductor may be substituted for the particular cartridge designed for use in the fuse plug and produce an operative device. Thus life and property are protected thereby.

The screw 34 is secured in the holder so as to swivel therein, by the disc 32. This is a simple and efficient construction.

In Fig. 5 is illustrated a construction wherein the recess 13^x extends the full length of the fuse body 5^x, and opens through the end thereof instead of terminating shortly below the gripping head as shown in Fig. 2. Upon the associated cartridge holder 12^x (see Fig. 6) I provide a lug 12^y which fits within and closes the bottom end of the recess 13^x when said cartridge holder has been inserted into a fuse body 5^x. A fuse body with a recess as shown in Fig. 5 may be more easily made because it can be readily withdrawn from the mould. The lug 12^y on the associated holder 12^x additionally insures correct registry of the parts and makes error in assembly quite impossible.

While in describing my invention I have referred to certain details of mechanical construction and arrangement of parts, I do not wish to be limited thereto except as pointed out in the appended claims.

I claim as my invention:

1. A fuse plug comprising, an insulating body having a contact shell at one end thereof, a fuse cartridge holder adapted to be inserted into the body from said shell end, a contact finger in the body, connected to the shell, said finger being adapted for engagement with the fusible member of the cartridge, and means carried by the holder and adapted to be actuated from the outside thereof to secure the cartridge, in the holder, said means forming the central contact member of the fuse plug.

2. A fuse plug comprising an insulating body having a contact shell at one end thereof, a fuse cartridge holder adapted to be inserted into the body from said shell end, a contact finger in the body, connected to the shell, said finger being adapted for engagement with the fusible member of the cartridge, and central contact member swiveled in the end of the holder and adapted to secure the cartridge in the holder.

3. A fuse plug comprising an insulating body having a contact shell at one end thereof, a fuse cartridge holder adapted to be inserted into the body from said shell end, a contact finger in the body, connected to the shell, said finger being adapted for engagement with the fusible member of the cartridge, and a screw carried by the holder and adapted to be threaded into the end of the cartridge to secure the same in the holder.

4. A holder for a fuse cartridge having a threaded opening in one end, said holder comprising a tubular body closed at one end, a screw mounted in the closed end of the body and having a head without said body, and a threaded end within said body and adapted to be screwed into the threaded hole in the end of the cartridge, to secure the same in the holder, and means in said holder and engaging the screw to permit a free rotative movement and a limited endwise movement of said screw with respect to said holder.
5. A holder for a fuse cartridge having a threaded opening in one end, said holder comprising a tubular body closed at one end, a screw mounted in the closed end of the body and having a head without said body, and a threaded end within said body and adapted to be screwed into the threaded hole in the end of the cartridge, to secure the same in the holder, and a disc in said holder of substantially a thickness equaling the pitch of the threads on the threaded end of the screw and through which said end is screwed, said disc engaging the screw and permitting a free rotative movement thereof and a limited endwise movement of the screw with respect to the said holder.
- 30 6. A holder for a fuse cartridge having a threaded opening in one end, said holder comprising a tubular member having a hole at one end which opens into the interior of the holder, a screw in said hole having an enlarged head without the holder and a threaded end within the holder adapted to be screwed into the threaded opening in the fuse cartridge, said head and threaded end of the screw being connected by a neck of smaller diameter, and a loose disc in said holder through which said threaded end is screwed and thereafter engages said threaded end in a manner permitting a free rotative movement of the screw and a limited endwise movement thereof with respect to said holder.
7. A fuse plug comprising, an insulating body having a longitudinal recess which opens through one end thereof, a threaded contact shell on said end of the body, a fuse cartridge holder adapted to be inserted into said recess, said body and cartridge holder having inter-engaging parts insuring correct insertion of the holder and preventing a relative rotation between the body and the holder, means carried by the holder for securing the cartridge therein and providing the other contact member for the fuse plug, and a spring contact finger in said body and connected to the shell, said spring contact finger being automatically engaged by a part of the cartridge when the holder is inserted into the recess.
8. A fuse plug comprising, an insulating body having a central recess which opens through one end of the body and a second recess which communicates with the first and opens through the side of the body, a threaded contact shell fixed on said end of the body, a spring contact finger in the second recess and connected to the contact shell, a fuse cartridge holder adapted to be inserted into the first mentioned recess, said holder having a part substantially closing off said recess when it is in position in said body, a fuse cartridge having one end of a fusible member arranged outside the holder and engaged by said contact finger and means associated with the exposed end of the holder for securing the cartridge in the holder.
9. A holder for a "tell tale tag" fuse cartridge comprising a tubular body having a head at one end, and a notch in the other end of the body, said body having a flattened portion in line with said notch, and with which the "tell tale tag" engages after being bent over and passed through the notch, and means carried by the head end of the holder for securing said fuse cartridge therein.
- In testimony that I claim the foregoing as my invention, I affix my signature in the presence of two witnesses, this 7th day of October A. D. 1921.
